UNITED STATES PATENT OFFICE.

RODNEY BALDWIN OSTERHOUDT, OF KINGSTON, NEW YORK.

GOLF-CLUB BAG.

Application filed April 5, 1923. Serial No. 630,133.

To all whom it may concern:

Be it known that I, RODNEY BALDWIN OSTERHOUDT, a citizen of the United States, residing at Kingston, in the county of Ulster and State of New York, have invented certain new and useful Improvements in Golf-Club Bags; and I do declare the following to be a full, clear, and exact description of the invention, such as will enable others skilled in the art to which it appertains to make and use the same.

In the ordinary types of golf bags, all of the clubs are carried indiscriminately in one compartment and when removing and replacing any of the wooden clubs, it is practically impossible to prevent them from being scarred by the metal clubs. Furthermore, when the wooden and metal clubs are carried in the same bag, there is danger of the metal wearing and cutting the wrappings which secure the spliced or socketed wooden heads to the shafts. To overcome this difficulty, it has been proposed to provide golf bags with separate compartments for the two kinds of clubs, but these bags have not been as neat in appearance as they might be and furthermore have been comparatively expensive and hence have not been readily accepted by golf players.

It is the object of the present invention to provide a two-compartment bag which will possess all of the advantages of somewhat similar bags heretofore designed, without the disadvantages thereof, the construction being such that the device may be easily and inexpensively manufactured and will present a neat attractive appearance.

With the foregoing in view, the invention resides in the novel subject matter hereinabove described and claimed, the description being supplemented by the accompanying drawing.

Figure 1 is a perspective view of a golf club bag constructed in accordance with my invention.

Figure 2 is an enlarged longitudinal sectional view, partly broken away.

Figure 3 is a horizontal sectional view on line 3—3 of Fig. 2.

Figure 4 is a detail vertical transverse sectional view as indicated by line 4—4 of Fig. 2.

Figure 5 is a perspective view of the rigid frame to which the upper end of the bag wall is secured.

In the drawings above briefly described,

the numeral 1 designates a rigid horizontal upper end frame in the form of an 8. Below this frame is a suitably covered bottom 2 having the same outline as said frame, 60 said frame and bottom being suitably secured to the upper and lower ends of a flexible side wall 3. The upper edge of this wall is preferably turned down around the frame 1 as indicated at 4 and suitably 65 stitched at 5, simultaneously establishing a strong connection between the wall and frame and obscuring the latter from view, with the exception of its connecting portion 6, which portion may have an appropriate covering 7.

The opposed portions of the side wall 3, in line with the contracted portion 6 of the frame 1 and the corresponding contracted portion of the bottom 2, are connected with each other, preferably by a line 75 of stitching 8, thus dividing the bag into two pockets, one of which may receive the wooden clubs while the other is used for carrying the clubs made of metal. 80

In the preferred form of construction, the side wall 3 is formed from a single sheet of material having its edges united by the line of stitching 8 which secures the opposed portions of the wall together as above described. 85 By this construction, not only is inexpensive manufacture provided for, but the seam connecting the edges of the material will be located between the two club pockets, at which point it is practically impossible to break any of the stitches by accidentally brushing the bag against objects. 90

The bag may be provided with any desired form of carrying handle 9 and straps 10, the latter being preferably secured to the 95 larger pocket to prevent collapsing of the smaller pocket by said straps. The bag is preferably provided on its exterior with an appropriate pocket 11 for carrying balls.

From the foregoing, taken in connection 100 with the accompanying drawings, it will be seen that an extremely simple and inexpensive golf bag has been provided, yet one which will be highly desirable and will overcome the difficulties encountered with 105 the forms of bags now commonly used. As excellent results may be obtained from the details disclosed, they are preferably followed in all substantial respects, but within the scope of the invention as claimed, 110 numerous minor changes may of course be made.

I claim:

1. A golf bag comprising a top frame in the form of an 8, a bottom having the same outline as said top frame, and a flexible side wall attached at its ends to said frame and bottom, the opposed portions of said wall in line with the contracted portions of said frame and bottom being connected with each other, dividing the bag into two separate containers for wood and metal clubs.
2. A golf bag comprising a top frame in the form of an 8, a bottom having the same outline as said top frame, and a flexible

side wall attached at its ends to said frame ¹⁵ and bottom, the opposed portions of said wall in line with the contracted portions of said frame and bottom being stitched together, dividing the bag into two separate containers for wood and metal clubs. ²⁰

3. A structure as specified in claim 2; said side wall being formed of a single sheet of material with its edges secured together by the stitching uniting said opposed portions of the wall. ²⁵

In testimony whereof I have hereunto affixed my signature.

RODNEY BALDWIN OSTERHOUDT.
